UNITED STATES PATENT OFFICE

SAMUEL LIPSCHUTZ, OF BROOKLYN, NEW YORK

INK CARRYING RESERVOIR

Application filed February 27, 1929. Serial No. 342,994.

This invention relates to fountain pens; more particularly, to receptacles for fluids, such as writing ink and to sealing or capping means holding writing fluid or similar fluids.

It is an object of my invention to provide, preferably in association with a fountain pen or similar device, a receptacle for retaining writing fluid whereby an auxiliary vessel is provided to replenish the supply of writing fluid or ink of the fountain pen, which auxiliary supply and receptacle therefor may be conveniently carried and furnish the required ink in an emergency, with no greater inconvenience in the size and bulkiness of the device than that usually occasioned by the normal-sized fountain pen. A still further object of my invention resides in the provision of an auxiliary receptacle or reservoir for supplying an emergency quantity of fluid, such as ink, which may be conveniently and compactly associated with existing types of fountain pens for use therewith, to replenish at will the normal supply of ink carried by the fountain pen. It is contemplated by my invention to provide an auxiliary receptacle for retaining writing ink of such compact size as to add no material increase in dimension to the normal fountain pen, the receptacle being capable of use with the so-called self-filler type of fountain pen, which is filled by the suction of a rubber sack through the nib or point of a fountain pen.

It is contemplated by my invention to so form the closure for a receptacle whereby the tipping of the pin or nib within the receptacle will serve to properly feed the requisite amount of fluid to the pen and leave the mouth of the receptacle in a condition whereby, upon application of the closure, overflowing of the device or soiling of the hands in handling the device will be avoided. It is still further contemplated by my invention to provide a receptacle capable of carrying fluids, such as writing ink and a closure therefor which will ensure against any leakage of the fluid, no matter in what position or condition the device is carried, whereby the receptacle and closure therefor may be conveniently associated with a fountain pen, particularly the cap thereof, to supply an

auxiliary reservoir or chamber for carrying an auxiliary supply of writing fluid which may be used to replenish the normal quantity carried in a self-filling fountain pen.

It is therefore still further contemplated by my invention to provide a receptacle for fluids, such as writing ink and a closure therefor, the receptacle and closure having a connecting joint to assure against leakage when in use, the device including an overflow safety seal whereby the receptacle may be filled to its full capacity without danger of soiling the parts handled by the user and, further, whereby the nib or pen point may be dipped into the receptacle, even when full, without danger of overflowing and soiling the parts normally handled by the user.

Still further objects of my invention reside in the provision of a receptacle for fluids, such as writing ink, and a closure therefor acting in the nature of a seal whereby the receptacle may be associated with a fountain pen, such as the cap thereof, of a size no greater than the normal dimensions of the fountain pen, the mouth of the receptacle being formed whereby the nib or point may be dipped therewith even when full without overflowing of the fluid about the mouth or neck of the receptacle, and soiling the hands of the user, at the same time providing an efficient seal for the receptacle whereby the same may be carried about in the pocket of an individual, in any position, without danger of overflowing or loss of the contents thereof.

Other objects of my invention reside in the provision of a new and novel construction in fountain pens providing compactness and leakproofness of those portions of a fountain pen which are to retain fluids, such as writing ink, whereby the same may be used in connection with auxiliary receptacles or other parts thereof for retaining fluids, such as writing ink, all of which will be neat and attractive and simple and inexpensive to manufacture.

To attain these objects and such further objects as may appear herein or be herein-after pointed out, I make reference to the accompanying drawings forming a part hereof, in which—

Figure 1 is a plan view of an embodiment of my invention;

Figure 2 is an enlarged fragmentary section taken on the line 2—2 of Figure 1, showing my device attached to a fountain pen, and particularly the cap thereof;

Figure 3 is a perspective view of a detail of the receptacle;

Figure 4 is a fragmentary sectional view 10 of another embodiment of my invention showing an integral cap construction;

Figure 5 is a plan view of another embodiment of my invention;

Figure 6 is a section taken on the line 6—6 15 of Figure 5;

Figure 7 is a still further embodiment of my invention;

Figure 8 is another embodiment of my invention as shown in connection with a fountain pen nib;

Figure 9 is a still further embodiment of my invention showing a cap, receptacle and clip arrangement.

Making reference to the drawings, in one embodiment of my device I show a fountain pen 10 of the self-filler type, utilizing the popular type of rubber sack actuating lever 11. The fountain pen body includes a cap 12, of general tubular character, within 20 which the fountain pen nib or point 13 is disposed by screw threaded means 14, serving to drive the shoulder of the pen 15 against a flange 16, retaining the same in rigid contact and protecting the point from the upper wall 17. Preferably, I form the upper portion 18 of the tubular section of the cap 12, 25 interiorly thereof with screw threaded walls 19, into which I dispose the auxiliary vessel 20. I provide the auxiliary vessel 20 at its lower portion with a cylindrical portion 21, 30 which is also screw threaded, arranged to be received within the screw threaded portion 19, previously described, and this screw threaded portion may be stepped off to provide a shoulder 22 to bear against the rim 35 of the upper portion of the tubular section previously described.

The vessel 20 as thus provided has a neck portion 23 disposed from the shoulders 24. 50 The neck 23 is extended to form a butt-joint 24' and the neck thus formed is preferably a thin-sectioned, tubular portion, about which and spaced therefrom there is provided an additional sealing wall 25, forming therebetween a slot 26, at the bottom of 55 which, extending into the receptacle, there are provided drain orifices 27. A cap 28 is arranged to form a closure for the vessel and this comprises concentrically formed walls 60 29 and 30, the inner wall 29 being of the same 65 general size as the slot 26 hereinbefore described, to make a tight fit within the slot 26. The outer wall 30 is interiorly preferably threaded at 31 to engage the screw threaded 70 section 32 on the exterior of the wall 25. This

threaded section is spaced away from the outer periphery of the vessel 20 to provide a shoulder 33. The cap as described may therefore be screw threaded over the vessel, so that the shoulder 33 is engaged by the edge 34 of the cap, to make a tight fit therewith. When so screw threaded upon the vessel, the wall 29 will be disposed between the neck 23 and the wall 25, extending into the spaced portion 26, until its edge extends to the bottom of the spaced slot 26. The dimensions of the spaced slot 26 and the neck 23 and wall 25 being substantially the same as the walls 29 and 30 of the cap, these sections will fit snugly, forming butt-joint engagement, as well as side wall engagement.

Interiorly of the cap 28 I preferably dispose a gasket 35, which is arranged to bear against the butt joint 24, serving as an interior seal. The complementary sections thus described form an efficient seal for the vessel 20 by reason of the numerous joints provided, as well as the sinuous path between the plurality of spaced complementary walls of the vessel and cap.

For use in the preferred form, the nib or point 13 may be disposed through the neck 23, to fill the fountain pen in its ordinary way. It will be observed that when dipping the nib 13 into the neck of the vessel, even though the neck is substantially the same size as the nib or pen point and with the vessel 20 filled with ink or similar fluid, the displacement of ink caused by introduction of this member, even should the vessel be full, will not cause an overflow of the ink to the exterior as the ink will first overflow over the edge 24 and then into the space 26. Ink so overflowing may drain back into the interior of the vessel through the orifices 27. Also, if the pen is filled by suction into the fountain pen, the orifices 27 will permit ingress of air for the ink removed, assuring a flow of ink into the fountain pen, as well as draining the space 26 of any ink which may have been caused to overflow thereto. It will be further observed that after filling the fountain pen, the cap 28 may be placed into position and any ink which may be disposed in the space 26 will be forced into the vessel itself and clear the same of any fluid which may be contained therein, preventing its escape to the interior of the vessel, and thereby avoiding soiling the hands of the user.

In all, I have provided an efficient seal for the vessel in addition to providing a safety overflow for a vessel having a neck of such constricted size wherein I may use this vessel to insert a nib or point of ordinary size without danger of soiling the hands of the user by overflowing of the ink, thus retaining the entire vessel of a size which may be readily associated with the cap of a fountain pen, without unduly increasing the size of the entire device and defeating the purposes of con-

venience of associating these devices into one article.

In Figure 4 I have illustrated my novel device wherein the cap 12' of a fountain pen has integrally formed thereon a vessel 20', the bottom wall 21' being molded, turned or otherwise formed from the material normally used for the fountain pen cap. A neck 23' and closure 28' are provided as in the embodiment described in Figures 1, 2 and 3. In the embodiments thus far described, it will be observed that though it is preferred that the interior of the closure make screw threaded engagement with the vessel, I may have a friction fit between these two parts and due to the sinuous path provided by the spaced walls corresponding to the neck 23 and 25 and the supplemental walls 29 and 30 on the closure and the butt-joints, as previously described, the closure will form an efficient seal for the vessel in addition to the advantages previously described in using the device to fill the fountain pen, both in inserting the fountain pen into the vessel and actual sucking of the ink or writing fluid therefrom.

In Figures 5 and 6 I have illustrated a vessel 36 in the nature of a small capsule which may be conveniently carried about in the vest pocket or the like so that it need not be associated directly with the fountain pen or the cap thereof. This vessel is provided with a neck 37 and closure 38 of the same construction as previously described in connection with the neck 23 and closure 28, in the embodiment where I use my invention in association with, or as part of, a fountain pen. Thus, I have provided a small vessel or capsule which may be conveniently carried about without any undue bulkiness in size, to have in readiness a quantity of ink for replenishing the normal supply of ink carried by a fountain pen.

In Figure 7 I have illustrated my invention as associated with another form of a readily portable vessel. In this embodiment, receptacles 39 and 40, preferably box-like members of similar size, are hinged to each other at 41. Interior of said box-like members there may be disposed capsules or vessels, such as 36, of dimensions fitting snugly within the boxes, leaving flanges 42 disposed above the upper wall 43 of the capsule. It will be understood, however, that the box-like members 39 and 40 may be made from a plastic composition, such as a phenolic condensation resin, known as bakelite, rubber or celluloid, integrally molded. In this form of device the neck and closures therefor 44 are disposed off center, leaving a clearance space 45, within each box-like member. The closures 44 and the neck which they serve to cover are of the same general construction as described in connection with the neck 23 and closure 28. These members may be hinged in superimposed position with the

closures 44, the closures 44 each nesting within the clearance portion 45. A snap fastener 46 serves to engage a lug 47 and hold the two sections 39 and 40 in the superimposed position. In this manner I provide two complementary vessels which may be used to hold additional quantities of writing fluid, preferably, if so desired, each of different color or quality.

It will be further observed that though I have described these devices as suitable for use for carrying writing fluid, other liquid material may be retained therein.

In Figure 8 I have described a still further embodiment of my invention wherein a fountain pen body 48 is shown associated with the closure contemplated by my invention. This fountain pen may be of the self-filler type or of the type wherein the ink chamber 49 may be filled by means other than the rubber sack or similar suction device provided in the usual fountain pen, such as by an eye dropper or pipette. The neck 50 is so formed as in the construction shown for the vessel 20 previously described and a closure 51 is provided, having the same general character as the closure 28. Through this closure, however, I may dispose the feed member 52 and nib 53 by providing an orifice 54. A gasket 55 is disposed immediately within the cap, corresponding to the gasket 35, and this is also similarly orificed to correspond to the general cross section of the feed member 52 and nib 53. In all other respects, the neck 50 and closure 51 include the elements of the neck and closure of the embodiments previously described and illustrated.

By this construction I provide the body of the fountain pen with an efficient closure, having all the features described in the receptacle of the previous embodiment.

In Figure 9 I have shown a still further embodiment whereby the receptacle 20 may serve to position and fix a fountain pen clip upon a cap of a fountain pen 12a. In this embodiment I provide a clip 55 having an anchoring ring 56, preferably integral therewith. This ring has the same general dimensions as the threaded neck portion 21 of the vessel and for purposes of affixing the clip in position, the ring is exteriorly disposed upon the neck and then the neck of the vessel is screw threaded upon the cap 12a. Thus I may quickly associate the vessel 20 with a fountain pen cap 12a, substituting for the clip holding means in this well known type of fountain pen clip, the vessel 20, the vessel providing the requisite means for holding the fountain pen, in addition to associating the desirable features of the receptacle.

Having thus described my invention and illustrated its use, what I claim as new and desire to secure by Letters Patent, is—

1. In an ink carrying receptacle including 130

a restricted neck arranged to substantially snugly fit a fountain pen and nib, a closure therefor, means for connecting said closure to said receptacle including a sealing joint for said neck comprising complementary snugly interfitting spaced walls on said neck and closure.

2. In an ink carrying receptacle, including a restricted neck, a closure therefor, means for connecting said closure to said neck including a sealing joint comprising spaced complementary annular interfitting walls on said neck and closure having means to drain the walls to the interior of said receptacle formed on said neck.

3. In an ink carrying receptacle, including a restricted neck, a closure therefor, means for connecting said closure to said neck including a sealing joint comprising a plurality of complementary snugly fitting, annular spaced walls on said neck and closure respectively having butt joint engagement between said walls and said closure.

4. In an ink carrying receptacle, including a restricted neck, a closure therefor, means for connecting said closure to said neck including a sealing joint comprising complementary snugly fitting, annular spaced walls on said neck and closure respectively having butt joint engagement between said walls and said closure and means for tensioning said closure in butt joint engagement comprising screw threaded members, said walls in the neck of said receptacle, including a drain, leading to the interior of said receptacle, and a complementary wall on said closure to clear said walls in positioning the closure.

In witness whereof I have hereunto signed
40 my name this 25th day of February, 1929.

SAMUEL LIPSCHUTZ.
